[57] **CLAIM**

The ornamental design for decalcomania for china dinnerware or similar article, as shown and described.

DESCRIPTION

FIG. 1 is a top plan view of a decalcomania for china dinnerware or similar article showing my new design; FIG. 2 is a top plan view of a second embodiment of my new design of FIG. 1; and,

FIG. 3 is a top plan view of a third embodiment of my new design of FIG. 1.

The fragmentary broken line showing of the transfer surface in FIGS. 1-3 is illustrative of environment structure only and forms no part of the claimed design. The decalcomania is of no substantial thickness.
